ATTORNEY.

UNITED STATES PATENT OFFICE.

SAM MEYER, OF ST. LOUIS, MISSOURI.

VENTILATOR FOR SHOW-WINDOWS.

1,381,326.

Specification of Letters Patent. Patented June 14, 1921.

Application filed October 22, 1918. Serial No. 259,215.

To all whom it may concern:

- Be it known that I, SAM MEYER, a citizen of the United States, residing at the city of St. Louis, State of Missouri, have invented 5 a certain new and useful Improvement in Ventilators for Show-Windows, of which the following is a specification, reference being had to the accompanying drawings, forming a part thereof.
- 10 This invention relates to a certain new and useful improvement in ventilators for show or display-windows.
- In modern merchandising establishments, for the purpose of displaying merchandise 15 to, and thereby attracting the patronage of, pedestrians upon the street, portions of the lower floor space at the front of the building are generally partitioned off from the interior floor space and built or provided 20 upon the street side with transparent glass affording a view into the show or display window. In cold or wintry weather particularly, due to the difference in temperature between the outside atmosphere and 25 the interior of the show-window, the glass frequently becomes frosted, the view into the show-window being thereby obstructed or impeded and the purpose of the show-window being thus neutralized. To obviate 30 the view of pedestrians into the show-window being so obstructed, is the chief object of my present invention; and with this object in view, my present invention resides in the provision of certain novel and efficient 35 ventilating-members adapted to be arranged or built in the window both above and below the glass front of the window, whereby cold air from the exterior may be permitted to find passage into the show-window and a 40 circulation of air in the show-window be produced, the inner surface of the glass front being thereby maintained at relatively as low a temperature as the outer surface of the glass front and frosting thereof con- 45 sequently prevented, and in certain novel features of form, construction, arrangement, and combination of parts, all as will hereinafter be described and afterward pointed out in the claims.
- 50 In the accompanying drawings,
- Figure 1 is a broken vertical sectional view of a portion of a show-window equipped with ventilating-members of my invention;
- 55 Fig. 2 is a front elevational view of the transom-bar of the show-window, showing the outer screened end of the upper ventilating-member;
- Fig. 3 is a fragmental plan view of the floor of the show-window, showing the inner 60 end of the lower ventilating-member;
- Fig. 4 is a longitudinal sectional view taken approximately on the line 4—4, Fig. 3; and
- Figs. 5 and 6 are enlarged perspective 65 views of a pair of the ventilating-members. Referring more particularly to the said drawings, in which like reference characters refer to like parts throughout the several views, 1 indicates the sill, 2 the store-front, 70 3 the transom-bar, 4 the floor, 5 the ceiling, 6 the cellar-bulkhead, and 7 the window-glass of a show-window of usual or general construction.
- The upper ventilating-member A, which 75 is a rectangular hollow metallic shell open at its inner and outer ends, as at 8 and 9, respectively, is mounted flatwise in the transom-bar 3, as shown, with its inner end 8 presented toward and communicating with 80 the interior of the show-window and its outer end 9 presented toward the exterior of the building and communicating preferably with atmosphere. At its outer end 9, the upper and lower walls of member A are preferably 85 flanged or bent inwardly upon themselves, as at 10—10, to provide a neat finish; and fixed flatwise upon the outer surface of transom-bar 3 and over the outer end 9 of the member A, and in a large measure pre- 90 venting the entrance of dust-particles and the like from the exterior into the member A, is a perforated face-plate 11. At its inner end 8, the upper and lower walls of member A are oppositely bent or flanged 95 outwardly to provide tracks or ways 12—12 for a pair of oppositely disposed independent inner-end-closing slides 13—13, each of which is flanged at its sides, as at 14—14, into sliding engagement with the tracks or 100 ways 12. The slides 13 are of a combined length substantially equal to the length of the open end of the ventilator and are independently movable toward and away from each other, by which arrangement it is pos- 105 sible to adjust the slides to afford an opening of any desired area and at any desired point between the ends of the opening in the shell. Adjacent its inner end, each slide 13 is pro- 110 vided with an inwardly disposed stud or pin

15 adapted to engage a side wall of the member A to limit the opening movement of the slide.

The lower ventilating-member B, which 5 is a hollow metallic shell made up preferably integrally of two communicating portions or legs 16—17 disposed at right angles one to the other, the shell B being similarly open at its inner and outer ends, as at 18 and 19, 10 respectively, is mounted in the show-window with its somewhat longer leg 17 disposed approximately flatwise beneath the sill 1 with its end 19 presented toward the exterior of the building and communicating 15 with atmosphere. The other leg 16 of shell B is disposed approximately vertically between the floor 4 and inner face of the sill 1, as shown, its open end 18 being presented toward and communicating with the interior 20 of the show-window closely adjacent the inner face of the glass 7. At its outer end 19, which projects slightly beyond the plane of the front 2, the upper and lower walls of shell or member B are also oppositely bent or flanged outwardly to provide 25 tracks or ways 20—20 for a pair of oppositely disposed closing-slides 21—21, each of which is similarly bent at its sides, as at 22, into sliding engagement with the tracks or 30 ways 20. At its inner end 18, which projects slightly above the plane of the floor 4, the shell B is likewise and similarly provided with tracks or ways 23—23 for a pair of similar closing slides 24—24 similar in construction 35 and operation to the slides 18 of the upper member, and as hereinbefore described; and surrounding the inner end 18 of the shell B and screwed or otherwise fixed to the floor 4, is a plate 25 adapted not only to 40 provide a neat trim for the inner end of the shell B within the show-window, but also a smooth surface upon the floor 4 for the slides 24—24 in opening and closing. Each slide 21 and 24 is likewise provided with 45 a stud or pin 26 adapted to engage a side wall of the shell or member B to limit the opening movement of the particular slide.

In warm weather, the several slides are usually closed. In cold or wintry weather, 50 or whenever it is desired to regulate the temperature of the show-window relatively to the temperature of the outside atmosphere, the several slides are suitably manipulated to open position, when, as will be 55 evident, cold air from the outside will flow through the lower ventilating-member or shell B into the show-window closely adjacent the glass 7. The entering cold air will strike the inner surface of the glass 7 and 60 circulate more or less within the show-window, the warmer air finding exit to atmosphere through the upper ventilating-member or shell A. The temperature within the show-window will soon approximate the 65 temperature of the outside atmosphere, and

consequently view-obstructing frosting of the glass 7 will be obviated. It will be understood that, while I have shown but one pair of the ventilating-members A and B, the show-window will be equipped with any 70 desirable number of said members suitably disposed in properly spaced relation above and below the glass 7, as described.

In the installation of my ventilator system, the upper and lower ventilating members 75 are preferably located one above the other or in substantial vertical alinement, and by the provision of the two independently movable slide members at the openings in the respective ventilator members, it is possible 80 to adjust the slides to afford openings in the respective members of the same or different areas and also to position the openings in the respective members into or out of vertical alinement, as conditions may require 85 or make it necessary to provide proper ventilation.

My new show-window ventilating-members A and B may be economically and cheaply manufactured and conveniently operatively installed and mounted in connection with the show-window, each member B being preferably rigidly fixed in position by means of one or more securing screws or the like 27 projected therethrough and 95 into a filler-block 28 disposed beneath and, in turn, fixed to the sill 1.

I am aware that minor changes in the form, construction, arrangement, and combination of the several parts of my new 100 show-window ventilators may be made and substituted for those herein shown and described without departing from the nature and principle of my invention.

Having thus described my invention, what 105 I claim and desire to secure by Letters Patent is:

1. A show window ventilator, comprising a rectangular shell of extended width open at its ends and adapted to be fixed in the 110 wall of a window and affording communication between the outside atmosphere and the interior of said window, and a pair of independent slides mounted upon the open end of said shell and of a combined length 115 substantially equal to the length of the opening and adapted to be independently adjusted to afford openings of different area and at any desired point between the ends of the opening in the shell. 120

2. A show window ventilator, comprising a rectangular shell of extended width open at its ends and adapted to be fixed in the wall of a window and affording communication between the outside air and the interior of said window, a pair of independent slides mounted upon the said open end of said shell and of a combined length substantially equal to the length of the opening and adapted to be independently ad- 130

justed to afford openings of different area and at any desired point between the ends of the opening in the shell, and stops on said slides for limiting the opening movement of the slides.

3. The combination with a show window including a pane of glass and a frame therefor mounted in a wall, of an injector ventilator comprising a right-angled shell open at 10 its ends adapted to be permanently mounted in the wall and located below and adjacent to and along the inner side of the sill of the window frame for directing the air inwardly and upwardly through said injector 15 ventilator and along the glass of said window, an ejector ventilator comprising a

straight rectangular shell open at its ends and adapted to be permanently mounted in the upper rail of said window frame in substantial vertical alinement with the injector 20 ventilator, and means for controlling the passage of air through said injector and ejector ventilators, comprising a pair of independent slides fitted to the open ends of said ventilators and adapted to be independently adjusted to afford openings in the respective ventilators of the same or different areas and at the same or different positions in the respective ventilators.

In testimony whereof I have signed my 30 name to this specification.

SAM MEYER.
